LAMP HAVING A SLIDABLE SCREEN TO EX-
POSE ONE OR THE OTHER OF TWO DIF-
FERENT LIGHT SOURCES

Thomas Phils, New York, N. Y.

Application August 6, 1952, Serial No. 302,923

5 Claims. (Cl. 240—11.2)

1

This invention relates to electric lamps and more particularly to a combination fog light and lamp adapted to be used aboard ships.

It is a principal object of the present invention to provide a combination fog light and lamp which includes novel means for alternately illuminating a yellow fog bulb and an ordinary frosted white bulb depending upon whether it is desired to utilize the invention as a fog light or as a reading lamp.

It is another object of the present invention to provide a combination fog light and lamp which embody novel means for alternately screening a fog light and an ordinary lamp depending upon whether it is desired to utilize the invention as a fog light aboard ships or alternately as an ordinary reading lamp aboard ship.

It is still another object of the present invention to provide a combination fog light and lamp which includes novel means for permitting a pair of closely spaced bulbs to be screwed into their respective sockets without mutual interference.

It is still another object of the present invention to provide a combination fog light and lamp which includes an upstanding rectangular casing having at the top a yellow fog bulb and at the bottom an ordinary frosted bulb and a rectangular screen movable along the outside of the casing from top to bottom adapted to alternately illuminate and reveal a fog light or an ordinary bulb, depending upon the particular purpose it is desired to use the invention for.

Other objects of the present invention are to provide a combination fog light and lamp of the above type which is of simplified construction, inexpensive to manufacture, easy to operate, compact and highly efficient in operation.

For other objects and for a better understanding of the invention, reference may be had to the following detailed description taken in connection with the accompanying drawing, in which:

Fig. 1 is a perspective view of a combination fog light and lamp embodying the features of the present invention and showing it in use as a fog light;

Fig. 2 is a transverse sectional view taken along line 2—2 of Fig. 1 and showing the interior construction thereof;

Fig. 3 is a vertical sectional view taken on line 3—3 of Fig. 2 and showing the internal arrangement of the parts and

Fig. 4 is a circuit diagram showing the means for alternately supplying current to the fog light and the lamp.

Referring now in detail to the figures and in

the practice of my invention, there is shown a combination fog light and lamp, referred to collectively as 10, consisting of a casing 11 made up of substantially square top and bottom parts 12 and 13 connected at their corners by integrally formed vertical pillars 14 and 15. The corners of the top and bottom parts 12 and 13 and the outer sides of the vertical pillars 14 and 15 are rounded so as not to present any sharp edges when handling. The vertical pillar 15 is identical in shape with the vertical pillars 14 except that one side is wider for a purpose to be herein-after described. The top and bottom parts 12 and 13 are hollow, presenting inner top and bottom parts 16 and 17 for a purpose to be herein-after described.

The side edges of the top and bottom parts 12 and 13 are provided with rectangular recesses 18 adapted to receive the walls of transparent glass 19 secured thereto by rectangular brackets 20 as clearly shown in Figs. 1 and 3. One of the brackets 20 at the top and a corresponding bracket at the bottom are provided with lugs 21 for a purpose to be herein-after described.

25 In the further practice of my invention, I provide a screen 22 of opaque material, preferably plastic, surrounding the casing 11 on four sides and extending substantially one-half the length thereof and adapted to slide along the vertical pillars 14 and 15 from top to bottom of the casing limited at the extreme positions by the lugs 21 previously referred to. It should be obvious that the screen 22 when in either extreme position will act as a screen for either the top or lower half of the casing 11.

30 35 A conventional electric bulb socket 23 is located within the casing 11 at the bottom thereof and is rotatably secured to the upper side of the inner bottom 17 by means of a clamp 24 surrounding said socket and riding on a shaft 25 located in a pair of bearings 26 rigidly secured to the inner bottom 17 in conventional manner. An ordinary frosted, white bulb 27 is screwed into the socket 23. A yellow bulb 28 is likewise screwed into a socket 29 similarly rotatably

40 45 mounted by means of a clamp 30 surrounding the socket 29 and riding on a second shaft 31 located in a second pair of bearings 32 rigidly secured to the lower surface of the inner top 16 in conventional manner. It should be obvious that upon removing the clamps 24 and the wall 19 adjacent the shafts 25 and 31 that either of the sockets 23 or 29 may be rotated outwardly so as to permit the unscrewing of either the bulb 27 or the bulb 28 without interfering with the other bulb.

The bulbs 27 and 28 are connected in parallel

to a source of power not shown by means of wires 33 and male plug 34, each of the parallel circuits having a micro-switch 35 whereby to permit alternate lighting of the bulbs 27 and 28.

The vertical pillar 15 is provided at the middle thereof on the inner sides with a shoulder 36 integrally formed therein and adapted to receive the microswitches 35 in fixed relationship as clearly shown in Fig. 3. The shoulder 36 is further provided with horizontal holes 37 and 38 located one beneath the other and adapted to receive the spring indented buttons 39 as clearly shown in Fig. 3. The central portion of the holes 37 and 38 is enlarged and contains a spring 40 which normally urges the button 39 outwardly of the wall 19. The buttons 39 consist of a head 41 which normally extends outwardly of the wall 19, a shoulder 42 adjacent the head 41 and adapted to engage the spring 40 and a central shaft 43 extending inwardly of the wall 19 to terminate adjacent levers 44 of micro-switches 35. The top inner wall 16 is provided with holes 45 and 46 adapted to permit passage of the wire 33, the inner bottom 17 being similarly provided with holes 47 and 48 for the same purpose, the bottom 13 further having a hole 49 adapted to permit passage of the wire 33 to the male plug 34.

In operation, let us assume that it is desired to use the combination fog light and lamp as an ordinary reading lamp, in which case the screen 22 would be in the position shown in Fig. 3 resting on the lug 21 at the top thereof. The lower button 39, normally urged outwardly of the hole 38 by the spring 40, serves to maintain the screen 22 against downward displacement and at the same time permits the lower lever 44 to assume its natural position thereby closing the lower micro-switch 35 and illuminating the white frosted bulb 27, assuming the male plug 34 has already been connected to a female plug and source of power. The screen 22 conceals the upper interior of the casing 11 and also engages the upper button 39 at the head 41, forcing it inwardly of the wall 16 through the hole 37, compressing the spring 40 and forcing the shaft 43 inwardly of the wall 16 into engagement with the upper lever 44 thereby opening the upper micro-switch 35 and turning off the yellow bulb 28.

Assuming that it is now desired to use the combination fog light and lamp now as a fog light on board ship, the lower button 39 is pushed inwardly of the wall 16, permitting the lowering of the screen 22 to the position shown in Fig. 1 with the screen 22 resting on the lower lug 21. The upper button 39, normally urged outwardly of the hole 37 by the spring 40 serves to maintain the screen 22 against upward displacement and at the same time permits the upper lever 44 to assume its natural position thereby closing the upper micro-switch 35 and illuminating the yellow bulb 28, assuming the male plug 34 has of course been connected to a source of power. The screen 22 conceals the lower interior of the casing 11 and also engages the lower button 39 at the head 41, forcing it inwardly of the wall 16 through the hole 38, compressing the spring 40 and forcing the shaft 43 inwardly of the wall 16 into engagement with the lower lever 44 thereby opening the lower micro-switch 35 and turning off the white, frosted bulb 27.

It should now be apparent that there has been provided a combination fog light and lamp which includes novel means for alternately illuminating a yellow fog bulb and an ordinary white bulb depending upon whether it is desired to utilize

the invention as a fog light or as a reading lamp, and which also includes novel means for alternately screening the fog light and white bulb. It should also be apparent that there has been provided a combination fog light and alternate lamp which includes novel means for permitting a pair of closely spaced bulbs to be screwed in or out of their respective sockets without mutual interference. It should also be apparent that there has been provided a combination fog light and lamp which includes an upstanding casing having at the top a yellow fog bulb and at the bottom an ordinary frosted white bulb, and a rectangular screen movable along the casing at the outside thereof from top to bottom and adapted to alternately illuminate and reveal a fog light or an ordinary bulb, depending upon the particular purpose it is desired to use the invention for.

While various changes may be made in the detailed construction, it shall be understood that such changes shall be within the spirit and scope of the present invention as defined by the appended claims.

Having thus set forth and disclosed the nature of my invention, what is claimed is:

1. A combination fog light and lamp comprising an upstanding, substantially transparent casing, a first electric bulb located interiorly of said casing at the top thereof, a second electric bulb located interiorly of said casing at the bottom thereof, a screen of opaque material surrounding said casing on all sides and extending substantially one-half the vertical length thereof and adapted to slide from top to bottom of said casing, and means operable by said screen for alternately illuminating said first and second bulbs.

2. A combination fog light and lamp comprising an upstanding casing consisting of substantially square top and bottom parts, integrally formed, vertical pillars connecting said top and bottom parts, the side edges of said top and bottom parts having rectangular recesses, rectangular glass walls adapted to rest in said recesses, a plurality of rectangular brackets adapted to secure said glass walls within said recesses, a first electric bulb located interiorly of said casing at the top thereof, said first bulb being yellow in color, a second electric bulb located interiorly of said casing at the bottom thereof, said second bulb being white in color, a screen of opaque plastic material surrounding said casing on four sides and extending substantially one-half the vertical length thereof, said screen being further adapted to slide from top to bottom of said casing, and means operable by said screen for alternately illuminating said first and second bulbs.

3. A combination fog light and lamp comprising an upstanding casing consisting of substantially square top and bottom parts, integrally formed, vertical pillars connecting said top and bottom parts, the side edges of said top and bottom parts having rectangular recesses, rectangular glass walls adapted to rest in said recesses, a plurality of brackets adapted to secure said glass walls within said recesses, one of said pillars being provided at the middle thereof with an integrally formed shoulder, a pair of micro-switches rigidly secured to said shoulder at the top and bottom thereof, said shoulder having a pair of horizontal holes connecting the interior with the exterior of said casing, said holes being located one above the other in a vertical spacing, a pair of buttons located within said holes, the

central portion of said shoulder having enlarged holes surrounding said first mentioned holes, a pair of springs located within said enlarged holes, said buttons consisting of a head which normally extends outward of the shoulder, a shoulder adjacent said head and located within said enlarged holes and engageable with said spring, and a central shaft extending inwardly of the shoulder, a pair of activating levers extending from said micro-switches and terminating adjacent said shafts of said buttons, said shafts being normally urged out of engagement with said levers by said springs, a first electric bulb located interiorly of said casing at the top thereof, a second electric bulb located interiorly of said casing at the bottom thereof, each of said bulbs being electrically connected in parallel with each other and in series with one of said micro-switches, said micro-switches and said bulbs being electrically connected with a source of power, and a screen of opaque material surrounding said casing on four sides and extending substantially one-half the vertical length thereof, said screen being adapted to slide from top to bottom of said casing and further adapted to alternately engage the head of one of said buttons when in an up position and the head of the other of said buttons when in the down position whereby to alternately illuminate said first and second bulbs.

4. A combination fog light and lamp comprising an upstanding casing consisting of substantially square top and bottom parts, vertical pillars connecting said top and bottom parts, the four sides of said top and bottom parts having narrow rectangular recesses, four glass walls adapted to rest in said recesses and extending substantially the vertical length of said casing, eight removable brackets adapted to secure said glass walls to said top and bottom within said recesses, a first pair of bearings rigidly secured to the upper surface of said bottom at one side thereof and interiorly of said casing, a first shaft located within said first bearings, a first clamp having holes at the ends thereof adapted to rotate upon said shaft, a socket positioned within said first clamp and adapted to receive a bulb, a first bulb screwed into said first socket, a second pair of bearings rigidly secured to the lower surface of said top at one side thereof and interiorly of said casing, a second shaft located within said second bearings, a second clamp having holes at the ends thereof adapted to rotate upon said shaft, a second socket positioned within said second clamp and adapted to receive a second bulb, a second bulb screwed into said second socket, a screen of opaque material surrounding said casing on four sides and extending substantially one-half the vertical length thereof, said screen being further adapted to slide from top to bottom of said casing, and means operable by said screen for alternately illuminating said first and second bulbs.

5. A combination fog light and lamp comprising an upstanding casing including substantially square top and bottom parts, vertical pillars, connecting said top and bottom parts at the four corners thereof, the four edges of said top and bottom parts having narrow rectangular recesses

between said vertical pillars, for rectangular glass walls adapted to rest in said recesses between said vertical pillars and intermediate said top and bottom parts, said walls extending substantially the length of said casing, eight brackets adapted to secure said glass walls to said top and bottom parts within said recesses, means for releasably securing said brackets to said top and bottom parts, one of said pillars being provided at the middle thereof with an inwardly extending shoulder, a pair of micro-switches rigidly secured to said shoulder at the top and bottom thereof, said pillar and said shoulder having a pair of horizontal holes connecting the interior of said casing with the exterior, said holes being located one above the other in vertical spaced relationship, a pair of buttons located within said holes, said shoulder at the center interior thereof having enlarged holes surrounding said first mentioned holes, a pair of helical springs located within said enlarged holes, said buttons each consisting of a head which normally extends outward of the casing, an enlarged shoulder adjacent said head and located within said enlarged holes and engageable with said spring, and a central shaft extending inwardly of said shoulder adjacent said head to communicate with the interior of said casing, a pair of activating levers pivotally mounted within said micro-switches and extending therefrom, said levers terminating adjacent said shafts, said shafts being normally engaged by said springs and urged out of engagement with said levers, a first pair of bearings rigidly secured to the upper surface of said bottom at one side thereof and interiorly of said casing, a first shaft located within said first bearings, a U-shaped clamp having holes at the ends thereof adapted to rotate upon said shaft, a first bulb socket resiliently secured within said first clamp, a first bulb screwed into said socket, a second pair of bearings rigidly secured to the lower surface of said top at one side thereof and interiorly of said casing, a second shaft located within said second bearings, a second U-shaped clamp having holes at the ends adapted to rotate upon said shaft, a second bulb socket resiliently secured within said second clamp, a second bulb screwed into said socket, each of said bulb sockets being connected in parallel to a source of power by means of insulated wires and a male plug, said micro-switches being connected in series with said sockets, and a screen of opaque material surrounding said casing on four sides and extending substantially one-half the vertical length thereof, said screen being adapted to slide from top to bottom of said casing and further adapted to alternately engage the spring urged head of one of said buttons when in an up position so as to open the uppermost micro-switch, and the spring urged head of the other of said buttons when in a down position so as to open the lowermost micro-switch whereby to alternately illuminate said first and second bulbs while screening the other.
